GASTON DELPECH, OF NEMOURS, FRANCE, ASSIGNOR TO THE SOCIÉTÉ "QUARTZ & SILICE," OF PARIS, FRANCE, A CORPORATION OF FRANCE

APPARATUS FOR THE DRAWING OF TUBULAR ARTICLES

Application filed March 12, 1931, Serial No. 522,126, and in France March 23, 1930.

The manufacture of a tube of constant sectional area by the drawing of a plastic mass contained in a vessel requires conformation members (die or draw plate and mandrel). 5 The material to be drawn passes out by the free interval between these members. The profile of the pipe obtained depends on the shapes of the die and of the mandrel, and its sectional area depends on the speed of drawing. It follows from this, that in order to obtain regularity of the sectional area, in the course of the drawing, the relative position of the mandrel and die must be unchangeable. Now the mandrel cannot be fixed directly to the die since the production of a tube requires an annular space between the die and the mandrel. It is therefore necessary to extend the latter towards the interior of the vessel in order to carry well back its point 15 of fixation thereto. The mandrel in question then traverses obligatorily, at the time of the drawing, all or part of the molten mass.

In the particular case of the drawing of silica, this necessity does not involve any difficulties when the drawing vessel is at the same time the melting furnace and when the charge to be melted is constituted by silica in powder or in grains. It suffices to constitute this mandrel of a refractory material, 20 indeformable and without action on the silica being melted, and to fix the mandrel and the die to the furnace before melting, thereafter to charge the furnace and lastly to draw 25 when fusion is complete.

But I have ascertained that die-drawing gave better results when, instead of starting from a pulverulent primary material, a start was made from opaque or transparent silicia 30 already melted in a preceding operation and presenting itself either in the form of a tubular ingot, or in the form of a pounded block.

In these conditions, as the forces exerted on the mandrel by the charge are not uniformly distributed, it is impossible to avoid deviations of the mandrel in the course of the melting operation.

My present invention has for object a method of drawing allowing of starting from 50 a mass of any kind, even not perforated, and

ensuring in a sure manner among other advantages the fixity of the mandrel in relation to the die at the time of drawing.

The method consists in utilizing, in combination with a melting furnace having a 55 die, a mandrel arranged in such a way as to be able to move along its own axis and to pass through the molten material and to become centered, in relation to the die, in the desired position in which it is immobilized.

This mandrel is tubular in order to allow the passage of air as a result of the natural draught which is established in the interior of the latter, in such a way as to avoid soiling of the drawn product by the products 60 of reduction of the material subjected to the drawing operation.

My invention relates likewise to methods of displacement, fixation and line-checking 65 of the mandrel.

The accompanying drawing represents by way of example a view in vertical section of a form of construction of a group, furnace, die, mandrel, in accordance with the invention.

For the facility of the drawing it will be supposed that this furnace is cylindrical and that its axis is vertical.

The crucible 1 of a furnace, heated in any suitable manner (not represented) and suitably heat insulated in a casing, is fixed rigidly above the hole in a base plate 2, by means of a plate 3 and clamping columns 4. These columns 4 are extended upwards and support another three plates 5, 6, 7.

In the internally screw-threaded boss of the plate 5, there is engaged a tubular part 8 externally screw-threaded, provided at its circumference with operating handles 9 and comprising at its upper part a spherical cavity 10, in which there enters the lower part of a member 11. This member 11 forming a ball joint is extended upwards by a tube 12 and downwards by a locking sleeve 13, intended to support by locking screws 28 the carbon tube 14 forming the mandrel. The tube 12 carries also a heavy mass 16 intended to weight the whole. This tube 12 passes 80 at the centre of the aperture 17 in the plate 85

100

6 and at its upper extremity terminates in a pointer 15.

The plate 7 comprises at its centre a hole 18. Upon its upper face rests a plate 19 carrying a pointer 20.

The carbon tube 14 is provided at its lower part with a fixed collar 21 which constitutes the active portion of the mandrel, that which shapes the interior of the tube in the course 10 of drawing. It is provided moreover with a conical point 22, the tail of which is engaged with slight tightness, in the bore of the tube 14 at the extremity of the latter.

The crucible 1 narrowed down at its lower 15 part 23 is machined at 25 to receive without appreciable slack the ring 24 forming a die, in order to shape the exterior of the tube during the drawing. In this die 24 is likewise engaged a member 26 formed with an 20 axial hole and pressed against the lower face of the base 2 by locking clamps 27. The whole of the members 26 and 24 forms in the crucible a conical bottom.

The plate 6 carries three long screws 30 25 which allow at will of fixing the tube 12 in the position which it occupies in the vicinity of the center of the hole 17. Lastly the tube 14 comprises, at $\frac{2}{3}$ approximately of its part engaged in the furnace, a hole 31.

30 The operation is the following:

One commences by screwing down the seat 8 in the plate 5. Having thereafter withdrawn the plate 19, the group 12, 13, 14 is lifted in such a way as to free the upper 35 opening of the furnace. The primary material is then introduced into the furnace. Two cases can present themselves.

(1) If the primary material is in the form of a tubular ingot, the group 12, 13, 14 is 40 allowed to come back to the position represented in the drawing, passing through the hole in the ingot. Then the screws 30 are undone in order not to interfere with the deviations of the mandrel and the heating can then 45 be commenced.

(2) If the primary material is a solid block, the group 12, 13, 14 is left in the raised position, the tube 12 being clamped by the screws 13, and the heating is commenced.

50 When the temperature approaches that which is suitable for the drawing operation, the primary material softens and collects in the bottom of the furnace. In the first case (tubular ingot), it surrounds the mandrel.

55 In the second case (solid block), this instant is chosen to undo the screws 30, in such a way as to free the group 12, 13, 14 and to allow it to descend slowly like a punch under the effect of its weight, through the soft mass.

60 This descent requires for example one minute. Care will be taken to unscrew sufficiently the screws 30 in order that, at the end of the stroke, the point 22 sliding on the conical bottom may center itself perfectly in 65 the axial hole of the member 26, without

being troubled in its movement, whatever may have been the deformations of the tube 14 in the course of the heating.

After a short time the temperature suitable for the drawing operation is attained. The members 8 forming the seat is then unscrewed until it is brought in contact with the ball 11, which has for effect to maintain the group 12, 13, 14 in a well defined position, which is checked by removing the plate 19 so as to allow sight of the pointers 15 and 20; the screws 30 are then locked with care in such a way as not to destroy the alignment of the pointers. It is easy to understand that at this moment the mandrel proper constituted by the collar 21 occupies, in relation to the die 24, the exact position which one desires to see it occupy, and that the centering member 26 can be withdrawn without that position varying the least in 80 the world. It suffices then to continue the heating for a little while still in order that the molten material commencing to flow in the interval between the mandrel and the die, it may be possible to seize it, to draw it at 85 the desired speed, for example by the means provided in the French Patent No. 629,453 filed in the same name on the 4th May 1926.

In order to facilitate the beginning of the flow of the molten material in the interval 95 between the mandrel and the die, the plate 19 and the index 15 are removed, and there is engaged from the top in the group 12, 13, 14 a rod of carbon for example, by means of which pressure is exerted upon the tail of 100 the cone 22 which thus passes out of the tube 14.

It is pointed out that the mandrel formed by the group 12, 13, 14 is hollow and that there is established in the interior of the 105 mandrel at the moment of the drawing operating a natural draught. This arrangement has been recognized as indispensable. It has been ascertained in fact, that when it is not realized the interior of the drawn tube is 110 soiled by the products of reduction which becomes condensed therein. In the case of silica, there is found a deposit of a very hard brown substance. This substance which answers to the formula SiO is derived from the partial reduction of the silica by the carbon. It suffices to ensure the passage of 115 air by natural draught in the interior of the mandrel in order to obviate these deposits.

It is preferable but not indispensable to 120 reset the pointer 15 in place in order that the draught may be effected through the hole 31 into the furnace itself, that is in the hot zone. In fact, if the draught is allowed to take place by the tube 12, the vapours of silica 125 condense against the wall of the latter and block it very rapidly, which may cause trouble for subsequent operations, but not prevent the draught which would then take place through the hole 31.

It is evident that all that has been said applies to the case where, with a view to obtaining certain complicated sections (tube with 2, 3 or 4 holes), it has been necessary to arrange in the die not one only but several mandrels.

It is likewise possible to utilize the axial displacement of the mandrel with a view to varying the sectional area of the drawn product. This is a possibility of adjustment which constitutes an accessory advantage of the method.

Lastly, if for convenience of the description, all which precedes relates to molten silica, it must be understood that this is only by way of example and that the process is absolutely general. It is applicable to the drawing of any mass, plastic or rendered plastic by a physical agent such as a rise of temperature.

What I claim is:

1. An apparatus for drawing tubular articles of the type described, which comprises in combination, a crucible having an opening at its lower end, a hollow mandrel movably supported with respect to said crucible so as to extend thereinto and adapted to cooperate with said opening so as to form therewith an annular passageway, a detachable bottom for said crucible adapted to obturate said opening and to cooperate with the lower end of said mandrel for accurately positioning the latter, means for removably fastening said bottom to said crucible, and adjustable means for fixing said mandrel with respect to said crucible, whereby the mandrel can be accurately positioned by means of the removable bottom, then securely fixed in that position with respect to said crucible, after which the detachable bottom is removed.

2. An apparatus according to claim 1 in which the hollow mandrel is adapted to have its inside placed in communication with the atmosphere at at least two points located at different levels, so as to create a natural draught.

3. An apparatus for drawing tubular articles of the type described, which comprises in combination, a crucible having a circular opening at its lower end, a hollow mandrel movably supported with respect to said crucible so as to extend thereinto and adapted to cooperate with said opening so as to form therewith an annular passageway, a conical point at the lower end of said mandrel, a detachable bottom for said crucible adapted to obturate said opening, the inside of said bottom having a conical shape for guiding the lower end of said mandrel and accurately centering it, means for removably fastening said bottom to said crucible, and adjustable means for fixing said mandrel with respect to said crucible, whereby the mandrel can be accurately centered by means of the conical removable bottom, then securely fixed in posi-

tion with respect to the crucible, after which the detachable bottom is removed.

4. An apparatus for drawing tubular articles of the type described, comprising in combination, a crucible having a circular opening at its lower end, a tubular mandrel movably supported with respect to said crucible so as to extend thereinto and adapted to cooperate with said opening so as to form therewith an annular passageway, a removable point of conical shape adapted to be fitted in the lower end of said mandrel, a detachable conical bottom for said crucible adapted to obturate said opening, said detachable bottom being provided with a central hole for receiving said removable point and thereby accurately center in said mandrel with respect to said opening, means for removably fastening said bottom to said crucible, and adjustable means for securely fixing said mandrel with respect to said crucible, whereby the mandrel can be accurately centered by means of the removable bottom, then securely fixed in that position with respect to the crucible, after which the detachable bottom is removed.

5. An apparatus for drawing tubular articles of the type described, which comprises in combination, a crucible having a circular opening at its lower end, a tubular mandrel movably supported with respect to said crucible so as to extend thereinto and adapted to cooperate with said opening so as to form therewith an annular passageway, said mandrel being provided with a hole for connecting its inside with the inside of the crucible above the level of the melted material therein, a removable point of conical shape adapted to be fitted in the lower end of said mandrel, a detachable conical bottom for said crucible adapted to obturate said opening, said detachable bottom being provided with a central hole for receiving said removable point and thereby accurately centering said mandrel with respect to said crucible, means for removably fastening said bottom to said crucible, and adjustable means for securely fixing said mandrel with respect to said crucible, whereby the mandrel can be accurately centered with respect to said opening by means of the detachable bottom, then securely fixed in that position, after which the detachable bottom is removed.

6. An apparatus for drawing tubular articles of the type described, comprising in combination, a crucible having a circular opening at its lower end, a tubular mandrel extending into said crucible adapted to cooperate with said opening so as to form therewith an annular passageway, means for movably supporting said mandrel with respect to said crucible, whereby said mandrel is allowed slight displacements in all directions, a detachable bottom for said crucible adapted to obturate said opening and to cooperate

with the lower end of said mandrel for accurately centering the latter, means for removably fastening said bottom to said crucible, means for checking the position of the
5 mandrel with respect to the crucible in the centered position, and adjustable means for securely fixing said mandrel with respect to said crucible, whereby the mandrel can be accurately positioned with respect to the crucible by means of the removable bottom, then
19 securely fixed in that position, after which the detachable bottom is removed.

In testimony whereof I have signed my
15 name to this specification.
